UNITED STATES PATENT OFFICE.

JOHN G. STOUGH AND URIAS C. STOUGH, OF DOVER, PENNSYLVANIA.

WINDMILL.

SPECIFICATION forming part of Letters Patent No. 338,203, dated March 16, 1886.

Application filed September 28, 1885. Serial No. 178,382. (No model.)

To all whom it may concern:

Be it known that we, JOHN G. STOUGH and URIAS C. STOUGH, citizens of the United States, and residents of Dover, in the county of York 5 and State of Pennsylvania, have invented certain new and useful Improvements in Windmills; and we do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of our improved windmill seen from above. Fig. 2 is a vertical sectional view of the same, and Fig. 3 is a top view.

Similar letters of reference indicate corresponding parts in all the figures.

Our invention has relation to windmills; and it consists in the improved construction and combination of parts of a windmill having means for governing the speed of the mill in winds of different strength, and having means 25 for overcoming the dead-centers upon the main crank-shaft, rendering it possible to run the mill in a very light wind, as hereinafter more fully described and claimed.

In the accompanying drawings, the letter A 30 indicates the frame of the mill, the upper end of which is formed into a circular grooved track or turn-table, B, upon which the circular frame C, upon which the wheel D is attached, rests, the said circular frame having a circular 35 groove, E, fitting over rollers F, interposed between the turn-table and the frame. The circular frame is provided with a downwardly-projecting flange at its outer edge, the lower edge, G, of which flange H is bent in under 40 the lower edge of the turn-table, the said flange and its inwardly-bent edge retaining the frame upon the turn-table. The main crank-shaft I is journaled in bearings J, upon the upper side of the circular frame, and has the wheel secured at one end, and is formed with two 45 cranks, K. An arm, L, projects from the circular track diametrically opposite to the wheel, and is provided at its outer end with an arm, M, projecting laterally at a right angle to it, and 50 the inner end of the steering-vane N is pivoted

upon the outer end of the arm projecting from the frame, swinging in a horizontal plane, and has two cords or chains, O and P, secured to its innermost end inside of its fulcrum, one, O, of which ropes passes over a pulley or bearing, Q, upon the circular frame, and down through the main frame of the mill, where it may be secured, while the other cord, P, passes over a pulley or bearing, R, upon the outer end of the outer arm, and is secured at its end 55 to a lever, S, pivoted at its inner end upon an inclined block, T, upon the circular frame, and provided at its other end with a weight, U. The inclined face of the block faces from the inner end of the vane, so that the weight will 60 cause the lever to descend easily, the descending lever drawing the inner end of the vane toward it and placing the vane in a plane parallel to the plane of the wheel, causing the wheel to stand with its edge toward the wind, 65 and consequently stopping the wheel. A pitman, V, is pivoted to one crank and passes down through the frame to the point where the power is needed, and two pitmen, W W, 70 are pivoted to the cranks, one of the pitmen being preferably pivoted to the head of the downwardly-projecting pitman, and are pivoted at their upper ends to the inner ends of two levers, X X, having their fulcrums upon the upper ends of two uprights, Y Y, upon the circular frame, and having adjustable poises Z Z 75 upon their outer ends, the said poises either having screw-threaded perforations, with which they turn upon the arms of the levers, or having smooth perforations sliding upon the 80 smooth arms and retained upon the same by set-screws. It will now be seen that as the wheel and the cranks are revolved the weighted levers will rock and by their momentum assist in carrying the cranks over their dead-centers, 85 thus serving to regulate the speed of the wheel and to render it more even, and the poises may be adjusted upon the lever-arms, so as to offer more or less resistance, by sliding them out or in upon the arms. The weighted levers will 90 in this manner act similarly to a fly-wheel upon a shaft, adding momentum to the revolutions of the shaft and keeping up the momentum, and, being adjustable upon the levers, 95 they may be adjusted according to the strength 100

of the wind. The flange having the inwardly-bent edge and projecting from the circular frame over the turn-table will retain the frame and rollers in place, and will at the same time 5 allow more space within the circular frame than where a sleeve projects from the frame and turns in the aperture of the turn-table, as is generally used in this class of wind-wheels. The anti-friction rollers interposed between 10 the circular frame and the turn-table will allow the frame and the wheel to turn easily to or from the wind, and the weighted lever having the cord attached to the inner end of the arm of the vane will draw the same parallel 15 to the wheel, and thus stop the wheel as soon as the other cord is released, the lever sliding downward upon the inclined face of the block, rendering the descent of the lever easy, while it retains the cord in nearly the same plane as 20 the arm of the steering-vane, rendering the pull upon the same more direct than if the lever was pivoted to swing vertically downward.

The wheel may be brought out of the wind in a moment by simply releasing the cord passing down through the frame, and may be brought in the wind by drawing the said cord, and the said cord may, if desired, be provided with a weight, instead of being secured, so that a sudden change of wind of greater strength 25 than it is desired to subject the wheel to will bring the wheel out of the wind by being forced back parallel with the wheel, and consequently bringing the wheel out of the wind.

Having thus described our invention, we 30 claim and desire to secure by Letters Patent of the United States—

1. In a wind-wheel, the combination of the circular frame bearing the wheel and provided with a rectangularly-bent arm diametrical-

ly opposite to the wheel, a steering-vane pivoted with its arm at the elbow of the rectangularly-bent arm, a pulley or bearing secured to the frame at one side of the vane-arm, a pulley or bearing secured at the end of the arm, a block having an inclined side facing away 45 from the vane and secured upon the frame at one side of the vane, a lever having a weight at its outer end and pivoted at its inner end upon the inclined face of the block, a cord secured to the inner end of the vane-arm and 50 passing over the pulley or bearing upon the frame, and a cord secured to the inner end of the vane-arm and passing over the pulley or bearing upon the end of the bent arm and secured to the weighted lever, as and for the 55 purpose shown and set forth.

2. In a wind-wheel, the combination of the main wheel-shaft formed with cranks, levers pivoted upon uprights and having weighted outer ends, and pitmen pivoted to the cranks 60 and to the inner ends of the weighted levers, as and for the purpose shown and set forth.

3. In a wind-wheel, the combination of the wheel-shaft formed with two cranks, levers pivoted upon uprights at the sides of the 65 shaft, poises sliding adjustably upon the outer arms of the levers, and pitmen pivoted at their lower ends to the cranks and at their upper ends to the inner ends of the levers, as and for the purpose shown and set forth. 70

In testimony that we claim the foregoing as our own we have hereunto affixed our signatures in presence of two witnesses.

JOHN G. STOUGH.
URIAS C. STOUGH.
